UNITED STATES PATENT OFFICE.

WILLIAM T. DOREMUS, OF NEW YORK, N. Y.

PILLOW AND BOLSTER.

SPECIFICATION forming part of Letters Patent No. 247,892, dated October 4, 1881.

Application filed August 23, 1881. (No model.)

To all whom it may concern:

Be it known that I, WILLIAM T. DOREMUS, of the city, county, and State of New York, have invented a new and useful Improvement 5 in Pillows and Bolsters, of which the following is a specification.

Reference is to be had to the accompanying drawings, forming part of this specification, in which similar letters of reference indicate corresponding parts in all the figures.

Figure 1 is a perspective view of my improvement. Fig. 2 is a sectional end elevation of the same.

The object of this invention is to prevent the 15 stuffing of pillows and bolsters from being crowded out of place by pressure applied to parts of the said pillows and bolsters.

The invention consists in a pillow or bolster 20 formed of a central roll surrounded by two or more parallel rolls connected with the said central roll along its sides, whereby the stuffing is kept from being pressed out of place by use, as will be hereinafter fully described.

The pillow or bolster is formed of a central 25 roll or core, A, surrounded by two or more parallel rolls, B, connected together along their parallel sides.

The pillow-cover can be formed of a continuous piece of ticking sewed together to form the 30 various compartments, as shown in the upper part of Fig. 2, the connection between the central roll and each surrounding roll being a single seam; or each surrounding roll can be connected with the central roll by two seams at a greater or less distance apart, as shown in the 35 lower part of Fig. 2. In the latter case there must be as many pieces of ticking used as there are rolls in the pillow, or the ticking between the central roll and the outer or surrounding rolls 40 must be made of two thicknesses. The central roll, A, can be stuffed with an inferior ma-

terial, and the surrounding rolls, B, can be stuffed with different materials, or with different quantities of the same material, to make some of the rolls harder than others, and thus 45 allow the user to have a harder or softer support for his head, as he may desire.

In using the pillow it can be adjusted for the head to rest upon one of the surrounding rolls B, or in the space between two rolls, B. 50

The ends of the central roll, A, are closed by circular or polygonal pieces of ticking sewed to the edges of the ticking that forms the body of the said roll. The ends of the surrounding rolls B can be closed by sewing the edges of 55 the ticking together in a seam tangential or radial to the central roll, A. The latter construction I prefer as making the surrounding rolls more readily adjustable; or the ends of the surrounding rolls B can be closed with separate pieces of ticking in the same manner as the ends of the central roll, A. The latter construction has the advantage of giving the pillow a uniform thickness from end to end. 60

Having thus described my invention, I claim 65 as new and desire to secure by Letters Patent—

1. A pillow or bolster made, substantially as herein shown and described, of a central roll surrounded by two or more parallel rolls connected with the said central roll along its 70 sides, as set forth.

2. In a pillow or bolster, the combination, with the central roll, A, of two or more parallel surrounding rolls B, connected along their inner sides with the said central roll, substantially as herein shown and described, 75 whereby the stuffing is kept from being pressed out of place by use, as set forth.

WILLIAM T. DOREMUS.
